Filed Mar. 17, 1970, Ser. No. 21,938

Term of patent 14 years

Int. Cl. D12—99; D26—06

U.S. Cl. D48—32

FIG. 1 is a rear elevational view of a fluted plano-aspheric lens showing my new design and illustrating the two types of flutes on the planar rear surface thereof;

FIG. 2 is a side elevational view of the lens shown in FIG. 1 illustrating the aspheric curvature on the frontal surface;

FIG. 3 is a front elevational view of the lens shown in FIGS. 1-2;

FIG. 4 is a cross-sectional view taken through FIG. 1 along the line 4—4 illustrating the fresnel-type flutes wherein the individual flutes have cross-sections which comprise portions of a continuous aspheric curvature; and

FIG. 5 is a cross-sectional view taken through FIG. 1 along the line 5—5 illustrating each of the remaining peripheral flutes to have a spherical segmental cross-section;

I claim:

The ornamental design for a fluted-plano aspheric lens, substantially as shown.
